TROWELLING TOOL

Dan J. Marx, 3572 Columbine Drive,
San Jose, Calif. 95127

Filed July 1, 1974, Ser. No. 484,607

Term of patent 14 years

Int. Cl. D8—05

U.S. Cl. D8—45

FIG. 1 is a perspective view of a trowelling tool showing my new design.

FIG. 2 is a side elevational view of the trowelling tool shown in FIG. 1 with the handle shown partially broken away.

FIG. 3 is a front elevational view of the trowelling tool shown in FIG. 1 with the handle shown partially broken away.

The illustrated trowelling tool includes an elongated handle, a blade holder attached to the handle, and a serrated blade carried by the holder. The design is particularly characterized in that the blade holder includes a thin, flat, platelike portion which angularly intersects a bifurcated thickened portion that receives and holds the trowelling blade. As is most clearly illustrated in FIG. 2 of the drawing, the angular break in the holder

causes the blade to be held at an angle relative to the handle. The design is also characterized in that the handle is thickened at the lower end and bifurcated to mate with the upper edge of the holder.

I claim:

The ornamental design for a trowelling tool, substantially as shown and described.
